RECORDING DEVICE FOR BLOCK SIGNAL SYSTEMS.

APPLICATION FILED JAN. 29, 1907.

3 SHEETS—SHEET 3.

UNITED STATES PATENT OFFICE.

TIMOTHY HALEY, OF XENIA, OHIO, ASSIGNOR OF ONE-HALF TO ALFRED G. BARNES, OF MACEDONIA DEPOT, OHIO.

RECORDING DEVICE FOR BLOCK-SIGNAL SYSTEMS.

No. 897,618.

Specification of Letters Patent.

Patented Sept. 1, 1908.

Application filed January 29, 1907. Serial No. 354,786.

To all whom it may concern:

Be it known that I, TIMOTHY HALEY, a citizen of the United States, residing at Xenia, in the county of Greene and State of Ohio, have invented certain new and useful Improvements in Recording Devices for Block-Signaling Systems, of which the following is a specification.

My invention relates to railway safety devices and particularly to a recording mechanism for use in conjunction with a railway block signal system.

The object of the invention is to provide a simple means of recording on the station train sheet the exact condition of the signal at the time a train enters the block and by thus registering the signal displayed provide means which will be beyond question for placing the responsibility in case of accident due to lack of attention or disregard of signals and by knowledge of its operation, inculcate greater care in the railway employees.

A further object is to simplify the construction as well as the means and mode of operation of such devices whereby they will not only be cheapened in construction, but are rendered efficient and positive in operation and unlikely to get out of repair.

With the above primary and other incidental objects in view, as will appear from the specifications, the invention consists of the means, mechanism, construction and mode of operation or their equivalents hereinafter described and set forth in the claims.

In the drawings, Figure 1 represents a perspective view of a block signal station showing the signal register and operating connections. Fig. 2 is a plan view of the register. Fig. 3 is a vertical sectional view of same. Fig. 4 is a plan view with the lid or cover removed and a portion of the train sheet torn away. Fig. 5 is a transverse sectional view on line X-X, Fig. 3. Fig. 6 is a perspective detail view of the marking device and the movable supporting member therefor. Fig. 7 is a detail plan view of same. Fig. 8 is a detail perspective view of a portion of the reciprocating member showing the guides for shifting the marking device. Fig. 9 is a detail perspective view of the train operated lever. Fig. 10 is a detail plan view of a modification of the marking device. Fig. 11 is a further modification of said device.

Like parts are indicated by similar characters of reference throughout the several views. 55

In the drawing, *a* is the semaphore adapted to display by the position of the arm during the day and by the colored light at night the signals "block closed", "proceed with caution" and "block clear" by the position 60 of the arm horizontal, inclined, or vertical or the lights red, green, or white in the usual manner. The semaphore is controlled by a lever *a*¹ within the station through a series of links and bell levers *a*². 65

Suitably located within the station and connected with the semaphore either by a separate system of links and levers or to the controlling lever *a*¹ and its connections is the recording mechanism as indicated at *b*. The 70 recording device consists of a case *b* having a hinged lid or cover. Located therein in suitable bearings is a supply roll *b*¹ and a receiving roll *b*² for a train sheet or strip *b*³. Guide rolls *b*¹² and *b*¹³ are provided about which the 75 train sheet is arranged. Slidably mounted in suitable ways *b*⁴ in said case *b* is a reciprocating member *b*⁵ over which the train sheet or strip *b*³ extends. Pivoted to support *b*⁵ on the member *b*⁵ is a pawl *b*⁷ engaging a ratchet 80 wheel *b*⁸ on the receiving roll *b*². To reciprocate the member *b*⁵ a link *b*⁹ is attached at one end the other being attached to a bell crank *b*¹⁰ which is oscillated by any suitable connection to the signal *a*. In the drawing 85 links *b*¹¹ having an intermediate bell crank are shown connecting the bell crank *b*¹⁰ with the operating lever *a*¹. The construction is such that at every movement of the lever to operate the semaphore the member *b*⁵ will be 90 given a corresponding movement; and every time the semaphore arm is moved to the "blocked" or "red" position the pawl *b*⁷ will engage the ratchet wheel *b*⁸ and advance the train sheet one space. 95

Located below the member *b*⁵ in vertical guides or ways *c* is a vertically movable supporting member *c* carrying in suitable ways 100 therein a movable marking device comprising a block *c*² having an upward projecting punch *c*³ registering with a corresponding die *c*⁴ secured to the lid or cover of the case *b*. The block *c*² is adapted to engage within the ways *c*⁵ of the supporting member *c* and is laterally movable therein. The upper portion of the block *c*² is beveled as at *c*⁶ or may 105

be provided with rollers as at c^7 , Fig. 10, to engage between flanges or guides c^8 secured to the lower side of the member b^5 . As said member is reciprocated the marking member 5 is shifted to different positions as shown by the solid, the dotted and the dot and dash lines of Fig. 7. The arrangement of parts being best shown by dotted lines Fig. 4. The supporting member c has a downward 10 projecting stem d projecting through a sleeve or guide d^1 in the bottom of the case b to which is connected a link d^2 attached at its opposite end to a rock arm e^1 , secured upon a rock shaft e . The rock shaft e is mounted on 15 suitable bearings e^2 and extends outside the station to a point in proximity to the rail of the railway track. Rigidly secured to the rock shaft e and adjacent to the railway rail is a contact or operating lever e^3 . The lever 20 e^3 protrudes above the rail in a position to be engaged and depressed by the wheels of a passing train. A compression spring f is located below the lever. It is obvious that the spring f may be otherwise located that it will 25 return the parts to normal position or a counterbalance device may be substituted. It is desirable that the spring f be of considerable strength necessitating several tons pressure to depress the lever e^3 to prevent 30 the operator working the actuating devices by hand to defeat the purpose of the invention.

In the cover of the case b are several openings. Through the first g of which the operator may record in writing the train number, 35 engine number, the time the train entered the block. In alignment with the opening g is a similar opening g^1 through which he may record other data and his signature. Above 40 the opening g is a space g^2 covered by glass to permit the identification record and time of several proceeding trains to be read while preventing any change being made in the record. Adjacent to the space g^2 and above 45 the level of the openings $g-g^1$ is an opening g^3 through which the time at which one or two proceeding trains pass out of the block may be registered when the time has been reported by the operator of the next block. 50 The train sheet b^3 is ruled to show the above mentioned data in parallel columns, and in addition three columns not visible to the operator when the case b is closed in which is indicated by punch marks or otherwise 55 the condition of the signal α when the train entered the block.

As the signal is operated the recording mechanism is set as before described and as the train passes over the lever e^3 it operates 60 to punch or mark in one of the three columns according to the signal displayed; the columns indicating from left to right "red", "green" and "white" respectively. Referring to the portion of the train sheet 65 shown in Fig. 4 it is indicated that train 27,

engine 143 received a "green" signal (to proceed with caution). The operator had, evidently, as is known in railroad parlance, "spiked the block" that is set the signal at "green" and left his post or gone to sleep. During this absence or sleep train 9 passed finding the signal still set at "green". As it is by the return of the signal to red after each train that the train sheet is advanced, the train sheet would not be moved after train 70 27 and before 9 and number 9 would punch the "green" registration in the same spot with number 27. Upon the operator's return he would call the next operator and learn what had passed during his absence 75 and enter train 9 as shown after operating the signal to advance the train sheet. However, train 9 would not be followed by a signal registration which would disclose the fact that the operator had been lacking in attention to duty. If he failed to get information from his neighbor and enter train 9 on the sheet, then his sheet would not tally, but would show one train less passed his station than passed through the block on either 80 90 side. Again referring to the train sheet it is shown that train 16, engine 721 entered the block at 4.01 o'clock under a "white" signal and was reported out of the block at 4.37 o'clock. The record of train 28 shows that 95 the train entered the block under a "red" or closed signal and if an accident should occur the responsibility would readily be placed on the train crew and not on the operator. The apparatus further insures the return of 100 the signal to red after each operation, otherwise the operator cannot prevent his neglect in this respect showing on the train sheet.

In Fig. 11 is shown a modification of the 105 marking device in which is employed three spring pressed punches h of different shapes, for instance round, triangular and square. The object being to provide distinguishing marks for the respective signals to be recorded in a single column. In this construction the block c^2 will be shifted in the same manner as before. Each punch h will have a spring h^1 tending to hold it elevated. Slots or openings h^2 are provided in the supporting member. When the recording mechanism is operated the punch h standing over the solid or unslotted portion h^3 of the member c will be thrust through the opening in the reciprocating member b^5 and engage the train sheet while the remaining punches contacting the member b^5 will be depressed against the tension of their springs; the lower ends extending through the slots h^2 as 110 115 shown in dotted lines.

It will be seen that there is thus provided a recording device possessing the particular features of advantage before enumerated as desirable but which is obviously susceptible 120 of modification in its form, proportion and 125 130

detail arrangement without departing from the principle involved or sacrificing any of its advantages.

Having thus described my invention, I claim:

1. In a device as described, a signal apparatus, an individual recording device, train operated actuating mechanism for said recording device, setting mechanism for said recording device acting synchronously with said signal apparatus, substantially as specified.
2. In a device as described, a signal apparatus, a train operated recording mechanism, a connection between said signal apparatus and said recording mechanism operated independent of the train for automatically adjusting said recording mechanism to correspond with the signal displayed, substantially as specified.
3. In a local station equipment, a signal apparatus, a train operated recording mechanism, means for automatically varying said recording mechanism to correspond with the signal displayed, substantially as specified.
4. In a device as described, a signal apparatus, a recording device, a connection between said signal and recording device whereby the setting of said recording device will be automatically varied in unison with the variation of the signal and means for completing the registration of the condition of the signal, substantially as specified.
5. In a signal station equipment, the combination with a signal apparatus, a recording mechanism, including a record sheet, means operated by a passing train for placing a permanent record on said sheet, and means for automatically varying the registering mechanism with the variation of the signal.
6. In a signal station equipment, a signal apparatus, individual recording mechanism including a case, a record strip in said case, means for advancing said strip through successive steps, means for indicating on said strip the condition of said signal apparatus at a predetermined moment, substantially as specified.
7. In a device as described, a signal apparatus, a recording mechanism controlled by the signal apparatus independent of the train including a case, a record strip, means for advancing said strip after each recording operation, a marking device adapted to indicate by its position on said strip the condition of said signal apparatus at the moment of registration and actuating devices for said recording mechanism, substantially as specified.
8. In a device as described, a signal apparatus, a recording mechanism comprising a case, a record strip, means for feeding same, a marking device, a shifter for said marking device, an operating connection between said shifter and said signal apparatus whereby said parts will move in unison, and actuating means for said recording mechanism, substantially as specified.
9. In a device as described, a signal apparatus, a recording mechanism, a record strip, a marking device, means for varying said marking device laterally to correspond with the movements of said signal apparatus, means for moving said marking device vertically to perfect the registration, substantially as specified.
10. In a device as described, a signal apparatus, a recording mechanism comprising a record strip, a marking device capable of longitudinal and vertical movement, means for automatically adjusting said recording device to correspond with said signal apparatus, means for moving said device to complete the registration, substantially as specified.
11. In a device as described, a signal apparatus, a recording mechanism including a record strip, a movable marking device movable guides arranged at an angle to each other and engaging said marking device, a train operated actuating mechanism connected to one set of said guides, the other guides being attached to said signal apparatus, substantially as and for the purpose specified.
12. In a device as described, a signal apparatus, a recording device comprising a case, a record strip, openings in said case for registering in writing the train identification, time operators' signature and other data, and train operated mechanism beyond the control of the operator for automatically registering the condition of the signal apparatus, substantially as specified.
13. In a device as described, a signal apparatus, a recording device comprising a record strip, a supply roll and a receiving roll for said strip, a ratchet wheel connected with one of said rolls, a reciprocating member connected with and moving in unison with said signal, a pawl carried by said reciprocating member and engaging said ratchet wheel to advance the record strip, a marking device adapted to engage said record strip and train operated mechanism for operating said marking device, substantially as specified.
14. In a device as described, a signal apparatus, a recording device including a record strip, means for feeding said strip, a marking device adapted by its lateral position to indicate the condition of said signal at the moment of registration, a reciprocating member connected to said signal and moving in unison therewith engaging means between said reciprocating member and said marking device for shifting said marking device laterally and train operated means for actuating said marking device, substantially as specified.
15. In a device as described, a signal apparatus, a recording device including a record

- strip, a marking device, suitable guides in which said device is movably supported, a reciprocating member, guides on said reciprocating member at an angle to said first mentioned guides and also engaging said marking device, means for giving to said member a reciprocating movement and means for bringing said marking device in engagement with the record strip, substantially as specified.
16. In a device as described, a signal apparatus, a recording device including a record strip having prescribed spaces corresponding to different conditions of said signal apparatus, a marking device adjustable to register with each of said spaces, a connection between said marking device and said signal whereby a movement of said signal will cause a corresponding movement of said marking device and train operated means for bringing the marking device into engagement with the recording strip, substantially as specified.
17. In a device as described, a signal apparatus, a recording device comprising a record strip, a punch, a die with which said punch registers, a connection between said punch and said signal train operated actuating mechanism whereby the record strip will be punched in predetermined positions to indicate the condition of said signal, substantially as specified.
18. In a device as described, a signal apparatus, a recording device including a record strip, a marking device, a vertically movable supporting member in which said marking device is movably supported, means connected with said signal apparatus for automatically adjusting said marking device, and train operated mechanism for vertically moving said supporting member, substantially as specified.
19. In a device as described, a recording device including a record strip, a marking device, a vertically movable member on which said marking device is supported, a rock shaft, a contact lever on said shaft located adjacent to the rail of the railway track, and in position to be depressed by passing wheels, a rock arm also on said shaft, a link between said rock arm and said vertically movable member, and means to return said parts to their normal positions, substantially as specified.
20. In a device as described, a signal apparatus, a recording device including a record strip, means for feeding said strip, a marking device, a vertically movable support on which said marking device is laterally adjustable, a reciprocating member, an operating connection between said reciprocating member and said signal apparatus engaging means between said reciprocating member and marking device for laterally shifting the marking device, a rock shaft, a train operated lever on said rock shaft, a rock arm and a link connecting said arm and said vertically movable support, substantially as and for the purpose specified.
21. In a signal station equipment, the combination with a railway signal of a recording device adapted to be varied in its adjustment through medium of said signal to automatically record the character of the indications displayed by said signal, substantially as specified.
22. In a signal station equipment, the combination with a signal, of a train operated mechanism for recording the intelligence indicated by said signal at the moment of the passing of the train, substantially as specified.
23. In a signal station equipment, the combination with a railway signal of a recording device controlled by said signal adapted to record a plurality of different indications, in accordance with different communications indicated by said signal, substantially as specified.
24. In a signal station equipment, a railway signal, a train operated recording device controlled by said signal and adapted to record the indications displayed by said signal, substantially as specified.
25. In a construction as described, a railway signal, a stationary mechanically operated recording device adapted to record the indications displayed by said signal upon appointed occasions, substantially as specified.
26. In a construction as described, a railway signal, a recording device therefor, mechanical connections between said signal and recording device to positively adjust said device upon variation of said signal, and means to perfect the registration, substantially as and for the purpose specified.

In testimony whereof I have here unto set my hand.

TIMOTHY HALEY.
